LIGHT SWITCH COVER

Ellen G. Barr, 469 Cypress Ave., Apt. 3,
Half Moon Bay, Calif. 94019

Filed June 6, 1975, Ser. No. 584,636

Term of patent 14 years

Int. Cl. D8—09

U.S. Cl. D8—179

FIG. 1.

FIG. 2.

FIG. 3.

FIG. 4.

FIG. 5.

FIG. 1 is an isometric view of a light switch cover embodying my new design;

FIG. 2 is a top plan view of the light switch cover shown in FIG. 1 (the bottom plan view is a mirror image of this top plan view);

FIG. 3 is a front elevation view of the light switch cover shown in FIG. 1;

FIG. 4 is a right side elevation view of the light switch cover shown in FIG. 1 (the left side elevation view is a mirror image of this right side elevation view); and

FIG. 5 is a back elevation view of the light switch cover shown in FIG. 1.

I claim:

The ornamental design for a light switch cover, substantially as shown and described.
